VARIABLE CAMBER PROPELLER BLADE
 Joseph C. Medisch and Clifford B. Wright, Indianapolis,
 Ind., assignors to General Motors Corporation, Detroit,
 Mich., a corporation of Delaware
 Filed Aug. 7, 1963, Ser. No. 300,491
 4 Claims. (Cl. 170—160.1)

This invention pertains to propeller blade constructions, and particularly to variable camber propeller blade constructions for variable pitch propeller blade assemblies.

Heretofore, blades of variable pitch propellers have been designed with a fixed camber that is a compromise to obtain the requisite cruise efficiency and take off thrust. It is recognized, however, that optimum cruise efficiency can only be obtained using a low camber airfoil, while maximum take off thrust can only be achieved with a high camber airfoil. The present invention is directed to a propeller blade construction having optimum propulsive efficiency by embodying two-position camber capability, the camber being automatically varied in accordance with the pitch position of the propeller blade.

Accordingly, among our objects are the provision of a variable camber propeller blade construction comprising a spar and a flap hingedly connected thereto throughout its length and constituting the trailing edge portion of the blade; the further provision of a variable camber propeller blade construction of the aforesaid type including means for automatically varying the camber of the blade in accordance with the blade angle, or pitch position, thereof; and the still further provision of a variable camber propeller blade construction including a spar, a flap and a segmented spacer assembly for closing the gap between the spar and the flap in both the low and high camber positions of the flap, and wherein the flap is pre-loaded throughout its length by cam actuated mechanism to eliminate flap flutter and preclude air flow through the hinge connection between the flap and the spar.

The aforementioned and other objects are accomplished in the present invention by embodying integral clevis portions in the trailing edge of the spar which, together with complementary clevis portions on the flap form a hinge adapted to receive a hinge pin. The spacer is formed in a plurality of sections, and is supported by the hinge pin between the spar and the flap so as to close the gap between the spar and the flap in both the low and high camber positions of the flap.

Further objects and advantages of the present invention will be apparent from the following description, reference being had to the accompanying drawings, wherein a preferred embodiment of the present invention is clearly shown.

In the drawings:

FIGURE 1 is a plan view, in elevation, of a variable camber propeller blade constructed according to the present invention, the blade being mounted in a hub socket.

FIGURE 2 is an enlarged fragmentary view, partly in section and partly in elevation, depicting the hinge joint between the flap and the spar.

FIGURE 3 is an enlarged fragmentary view taken along line 3—3 of FIGURE 1.

FIGURE 4 is an enlarged fragmentary sectional view taken along line 4—4 of FIGURE 1.

FIGURE 5 is a schematic view depicting the mode of operation of the variable camber blade of this invention.

With reference to FIGURE 1, a variable pitch propeller is shown including a hub 10 having a plurality of radially extending sockets, one of which is shown at 12. A variable camber propeller blade 14 is journaled for rotation about its longitudinal axis in the hub socket 12 by suitable bearing means, not shown. The propeller blade 14 includes a root portion 16 which may enclose

a torque unit of known construction for rotating the entire propeller blade at its longitudinal axis to vary the pitch position thereof. The pitch changing and control mechanism for the propeller blade constitutes no part of this invention, but may be of the type disclosed in Bodem et al. Patent 2,986,220.

The variable camber propeller blade comprises a spar 18 which, as shown in FIGURE 4, comprises a ribbed steel thrust member 20 that forms the blade shank, the root portion 16, the thrust face, and the leading edge of the propeller blade. A steel camber sheet 22 is copper brazed to the upstanding ribs of the thrust member 20 so as to form a thin, lightweight, high performance blade such as is well known in the art. A plurality of longitudinally spaced clevis portions 24 are machined as an integral part of the aft rib 26 of the thrust member 20. It is to be understood that the spaced clevis portions 24 extend through the entire length of the airfoil portion of the thrust member 20.

The blade 14 also includes a flap 28 forming the trailing edge of the blade 14. The flap 28, as seen in FIGURE 4, comprises a forged steel supporting member 30 having a plurality of longitudinally spaced clevis portions 32 interposed between the clevis portions 24 of the thrust member 20. The supporting member 30 constitutes a beam and has machined marginal edge surfaces 34 and 36 oriented at an angle of 10° to the aft rib 26. The flap 28 is completed by a pair of steel sheets 38 and 40 which are copper brazed to the supporting member 30 and roll welded to each other at the trailing edge 42, the cavity formed by the sheets 38, 40 and the supporting member 30 being filled with a low density polyurethane foam material. As shown in FIGURE 1, the spar 18 may be provided with an airfoil cuff portion 44 enclosing the shank of the propeller blade, which cuff may likewise be composed of a low density polyurethane foam.

Four metal spacer sections 46, 48, 50 and 52 are interposed and loosely mounted between the spar 18 and the flap 28, as shown in FIGURE 1. All of the spacer sections are apertured to receive and be supported by the hinge pin 58. As seen in FIGURE 4, the metal spacer section 48 has substantially flat machined marginal edge surfaces, the purpose of which will be pointed out hereinafter. It is to be understood that each of the spacers 46, 48, 50 and 52 is of similar construction. The inboard spacer 46, as shown in FIGURE 2, may have its exterior covered with rubber 54 to provide the necessary seal to accommodate the twisted profile of the spar and flap at the inboard end thereof, and all of the spacers have clevis portions 56 which are interposed between the clevis portions of the flap and the spar.

The spar, the flap and the spacer sections are hingedly interconnected by a longitudinally extending hinge pin 58 which extends throughout the length of the blade from the inboard end of the flap to the tip thereof. The shank of the spar 18 is formed with a support lug 60 which carries a thrust bearing assembly 62 for transferring the centrifugal loads imposed on the flap to the blade root 16.

The thrust bearing 62 is held in assembled relation with the support lug 60 by a bolt 64 having threaded engagement with the support member 30 of the flap 28. A hollow torque bar 68 encircles the shank of the bolt 64 and is rotatably journaled by the bearing 62. The upper end of the hollow torque bar 68 has a straight spline connection at 70 with the support member 30 of the flap 28, and the inboard end of the hollow torque bar 68 has a straight spline connection with an internally and externally straight splined indexing ring 72. A crank arm 74 is connected to the external straight splines of the indexing ring 72. The indexing ring 72 permits precise adjustment of the angular position of the flap 28 during assembly and enables aerodynamic matching of a

plurality of propeller blades in a multi-blade propeller assembly. The crank arm 74 carries a roller which rides in a cam track 78 attached to the flanged edge of the hub socket 12.

As seen particularly in FIGURE 3, the cam track 78 is formed with concentric grooves 80 and 82 of different radii, the grooves 80 and 82 being interconnected by an eccentric transition groove 84. A washer 86 is interposed between the head of the bolt 64 and the indexing ring 72, and the bolt is securely held in position by a suitable external lock 88.

The profile of the cam track 78 is correlated with the pitch position of the propeller blade so as to provide high camber at take off for maximum thrust, and low camber during cruise conditions. The roller 76 follows the cam track profile during pitch adjustment of the blade relative to its hub socket 12. Referring to FIG. 5, the flap 28 is shown in the high camber position in full lines and in the low camber position in phantom lines. The torque loads on the flap 28 are transferred to the propeller hub through the hollow torque bar 68 and the crank arm 74. In both the high and low camber positions of the flap 28, a seal is maintained at the hinge joint between the spar 18 and the flap 28 to prevent air leakage. Thus, as shown in FIGURE 4, when the flap 28 is in the low camber position the marginal edge 34 of the support member 30 engages the spacer members 46, 48, 50 and 52 throughout the length of the blade. When the flap member 28 is in the high camber position the marginal edge 36 of the support member 30 engages the spacer sections 46, 48, 50 and 52.

In the take off position of the propeller blade wherein the pitch position, or blade angle, is relatively low the flap 28 is rotated approximately 10° towards the thrust face of the spacer 18 to obtain a high camber airfoil for maximum take off thrust. As the blade angle is increased to the cruise position, the cam mechanism automatically rotates the flap to the low camber position where it completes the airfoil shape of the blade to obtain optimum cruise efficiency. In both the low camber and high camber positions of the flap 28, the flap is preloaded throughout its length from the contoured cam track 78 through the crank arm 74 by twisting it about its longitudinal axis due to abutment between one of the marginal edges 34 or 36 of the flap member 28 and the marginal edge surfaces of the spacer sections 46, 48, 50 and 52. This preloading reduces flutter and maintains the requisite seal between the flap, the spacers and the spar to preclude air flow through the hinge line. The hinge axis between the flap and the spar is a straight line so as to facilitate angular movement of the flap relative to the spar. During movement of the flap between the high and low camber positions, and vice versa, that is when the roller 76 is in the transition groove 84 of the cam, the flap is not twisted, or preloaded whereas in the operating positions the flap is twisted and acts as a torsion spring.

From the foregoing it is apparent that the present invention provides a variable camber propeller blade wherein camber variation is obtained by mechanically changing the angle of the trailing portion, or flap, of the blade chord about a longitudinal hinge axis. In a typical propeller installation the camber is increased from .25 to .75 with the resulting thrust increase of 24%. More-

over, the twist imparted to the flap in both the low and high camber positions to preclude flutter is in the order of 1° from the tip end of the flap to the inboard end thereof.

While the embodiment of the invention as herein disclosed constitutes a preferred form, it is to be understood that other forms might be adopted.

What is claimed is as follows:

1. A variable camber propeller blade comprising, a load supporting spar constituting a leading edge and the major portion of the thrust and camber surfaces of the blade, a trailing edge flap hingedly connected to said spar along a substantially straight line throughout its length, and spacer means loosely supported by the hinged connection between said flap and said spar for sealing the gap between said spar and said flap in both the low and high camber positions thereof.

2. A variable camber propeller blade comprising, a load supporting spar constituting a leading edge and the major portion of the thrust and camber surfaces of the blade, a trailing edge flap hingedly connected to said spar throughout its length, and a plurality of metal spacers loosely supported by the hinged connection between said spar and said flap for sealing the gap between said spar and said flap in both the high and low camber positions thereof.

3. The propeller blade set forth in claim 2 wherein said spar and said flap have interposed clevis portions defining a straight line hinge axis throughout its length, and wherein said hinged connection includes an elongate hinge pin extending through said interposed clevis portions on said spar and said flap.

4. A variable camber propeller blade including, a load supporting spar constituting the leading edge and the major portion of the thrust and camber surfaces of the blade, a trailing edge flap hingedly connected to said spar throughout its length, spacer means interposed between said spar and said flap, and means operable to rotate said flap between high and low camber positions in accordance with the pitch position of said blade comprising a cam track, a crank arm drivingly connected with said flap and having a follower disposed in said cam track, said driving connection between said crank arm and said flap including a torque rod and an internally and externally straight splined indexing ring whereby the angular position of said flap can be precisely adjusted to aerodynamically match a plurality of propeller blades, said cam track being contoured to twist said flap throughout its length from its tip end to its inboard end to eliminate flap flutter and said flap sealingly engaging said spacer means in both its high and low camber positions so as to close the gap between said spar and said flap.
